[57] ABSTRACT

A spindle unit for wrapping a covering yarn about a core yarn being drawn therethrough includes a spindle shaft supported by bearings within a hollow casing. The shaft includes a portion of substantially uniform cross section extending from the casing having a spindle whorl secured thereto. Pin members directed axially of the shaft and O-rings provided within grooves on the portion of the shaft having a uniform cross section drivingly engage yarn covering packages mounted thereon.

YARN-COVERING APPARATUS

BRIEF SUMMARY AND OBJECTS OF THE INVENTION

This invention relates to an improved mechanism for uniting a plurality of yarns, and more particularly to spindle assemblies for wrapping one or more inelastic yarns about a core yarn which is highly elastic.

The spindle assembly of the present invention has been designed for use in manufacturing composite yarns by combining a reversibly extensible strand, being drawn through the spindle assembly, with an irreversibly extensible strand mounted for rotation on the spindle assembly. The spindle blade is supported within vertically spaced antifriction bearings embraced by vibration damping collars and seated within the hollow casing. A core yarn is drawn through an axial bore extending through the shaft and combined with yarn being delivered from a package driven by the spindle blade. The package is received on the spindle blade and seated upon the whorl assembly. The whorl assembly is provided with pins for coupling the spindle with a covering yarn package. Upon high-speed rotation of the spindle, O-rings, vertically spaced above the whorl assembly on the spindle blade, tend to expand in such a manner as to grip and support internal portions of the covering yarn package to reduce vibrations of the spindle assembly.

One of the principal objects of the invention is the provision of a spindle assembly having novel arrangement of elements for producing a composite yarn by combining a core yarn with a cover yarn.

Another object of the invention is an improved high-speed spindle assembly which is simple in construction and highly reliable in operation.

A further object of the invention is the provision of a spindle assembly having apparatus for damping vibrations of the spindle blade and cover yarn package.

Still another object of the invention is a spindle assembly provided with an improved drive connection between the spindle shaft and a package mounted thereon.

Other objects and advantages will be readily apparent to those skilled in the art during the course of the following description of one embodiment of the present invention taken in conjunction with the accompanying drawings.

BRIEF DESCRIPTION OF THE FIGURES

FIG. 1 is a side elevational view of a portion of a machine for producing composite yarn showing the relationships of the spindle assemblies with various other component parts;

FIG. 2 is a side elevational view of the spindle assembly of the present invention having a yarn covering supply spool positioned thereon; and

FIG. 3 is a perspective view of the spool and spindle assembly with the housing removed from the bearing assemblies.

DETAILED DESCRIPTION OF THE INVENTION

Referring to the drawing in detail, FIG. 1 illustrates a conventional up twister machine 10 for winding covering yarns 12, 14 about a core yarn 16. The core yarn 16 is supplied from a package 18 which may be a stationary cone, wherein the yarn is drawn off from the end of the package, or from a freely rotatable or positively driven spool or bobbin package. The core yarn 16 which may or may not be in a twisted state of the package 18 extends through spindle assemblies 20 and 22, around rolls 24, 26 and is wound upon a takeup spool or bobbin 28 resting upon drive rolls 30, 32. Guide 34, carried by a traversing guide bar 36, moves back and forth in a conventional manner to lead the covered core yarn evenly from end to end of the takeup spool 28.

The spindle assemblies 20 and 22, substantially identical in form, have spools 37, 39 positioned thereon for supplying covering yarns 12, 14 that are to be wrapped on the core yarn 16. Each of the spindle assemblies includes a casing or housing 36 consisting of semicircular castings 38, 40 releasably secured together about bearing assemblies 42, 44 by screws 46

and a collar member 48. The screws 46 extend through lockwashers 54 and openings 52 drilled in the lower portions of casting 38 and are threadably received within apertures 54 provided in the casting 40. The external upper portions 56, 58 of the castings are threaded for receiving the threaded collar 48, as shown by FIG. 2. The collar 48 is locked in position on the housing 36 by a set screw 60 which may be tightened to bear against the upper portions 56, 58 of housing 36.

Each of the castings 38, 40 is provided with cavities 62, 64 for receiving bearing assemblies 42, 44 respectively, and with cavities 66, 68 for receiving the tubular spindle shaft 70 which has an axial bore 72 therethrough. The bearing assemblies 42, 44 are of a prelubricated type having the inner race rings 74 secured to the spindle shaft 70 as by press fitting or equivalent operations. The outer race members 76 receive an elastic vibration damping collar 78 which is of uniform cross section having a web portion 80 and flanged portions 82 for snugly gripping the outer race 76 radially and axially. When properly positioned on the race 76 the outer cylindrical surface of the vibration damping collar 78 fits snugly within the interior surfaces of the cavities 62, 64 provided in the castings 38, 40 of the housing 36.

A whorl assembly 84, positioned above the collar 48, is secured to the shaft 70 for rotating the spindle shaft and the yarn covering spool 37 or 39. The whorl assembly 84 includes vertically spaced flanges 86, 88 interconnected by an arched or crowned running surface 90 for receiving a driving belt 92. Diametrically opposed, axially extending drive pins 94 are secured to the upper flange 88 for driving engagement with a yarn covering package.

The enlarged upper and intermediate portions of the spindle 70 are provided with circumferentially extending radial grooves 96 having O-rings 98 therein. The radial grooves 96 and O-rings 98 are sized such that the outermost portion of the O-rings are flush with the outer circumference of the spindle 70 adjacent thereto. Upon high-speed rotation of the spindle 70 and the spool drivingly coupled thereto, the O-rings expand radially within the grooves 96 frictionally gripping the inner surfaces of the spool to reduce vibration of the spool and to provide a frictional driving engagement between the shaft and the spool.

Each of the yarn covering supply spools 37, 39 includes a tubular core or barrel member 100 having flanges 102, 104 at each end thereof. A plurality of openings 106, preferably four in number, are drilled into the barrel member at each end of the flanges 102, 104 for receiving the drive pins 94 secured to the whorl assembly flange 88. Bushings 108, within the barrel member 100, extend axially from each of the spool flanges 102, 104 sufficiently so as to be frictionally engaged by the O-rings 98 upon high-speed rotation of the spindle and spool.

The spindle assemblies 20 and 22 are supported upon vertically spaced rails 110 mounted upon the frame of the machine 10. Each rail 110 is provided with an opening, not clearly shown, for receiving the housing 36. Each housing 36 is rigidly secured to the rail by means of nuts 112, spaced on opposite sides of the rail and threadably received on the threaded central portion 114 of housing 36. Shock absorbers 116, which may be of rubber or other suitable material, are fitted between the frame 110 and the nuts 112 to insure smooth and vibration-free rotation of the spindle.

A guide member 118 is vertically positioned above each spindle assembly to restrict the balloon of the covering yarns created by the rotation of the spindles.

The core yarn 16 which may be of twisted or untwisted rubber, spandex or other yarns capable of elongation to several times its relaxed length, is stretched as it runs through the hollow spindle 70 by various means well known in the art. For example, the relative speeds of the supply package 18 and takeup package 28 may be controlled to stretch the yarn 16, or tension discs or feed rollers may be provided to tension the core yarn to a desired degree. Inelastic cover yarns 12 and 14 are wrapped about the core yarn 16 in its stretched condition and wound upon a package 28.

While the spindle assemblies, yarn supply means and takeup mechanisms for producing one composite yarn have been described, it is to be understood that the machine 10 normally comprises banks of such assemblies on both sides of the machine.

I claim:

1. In a machine for helically wrapping covering yarn about a core yarn, a textile spindle unit comprising: a stationary hollow casing for mounting on a machine frame member, bearing means positioned within said hollow casing, a spindle shaft rotatably supported by said bearing means within said hollow casing, said spindle shaft including a first portion of substantially uniform cross section extending from said hollow casing, said spindle shaft defining a bore extending axially therein adapted to have a core yarn drawn therethrough, means secured to first spindle portion for rotating said spindle shaft, and means on said first portion for supporting and drivingly engaging a yarn-covering package.

2. A spindle unit as defined in claim 1, wherein said means for supporting and drivingly engaging a yarn covering package includes a support plate extending radially of said first portion and drive pins extending axially of said first portion.

3. A spindle unit as defined in claim 2, wherein means for supporting and drivingly engaging a yarn covering package further includes expandable means on said first portion axially spaced from said drive pins.

5. 4. A spindle unit as defined in claim 3, wherein said expandable means includes an O-ring positioned within a radially opening groove provided on said first portion.

5. A spindle unit as defined in claim 1, wherein said spindle means comprise antifriction bearing means secured to said spindle shaft.

6. A spindle unit as defined in claim 5, further including vibration damping means attached to said bearing means and positioned intermediate said bearing means and said stationary casing.

15 7. A spindle unit as defined in claim 1, said means for supporting and drivingly engaging a yarn covering package including means spaced axially of said first portions displaceable into frictional engagement with a yarn package.

20 8. A spindle unit as defined in claim 7, said displaceable means comprising O-rings disposed in radial grooves provided in said spindle shaft first portion.
